N. A. CLARK

SOUND AMPLIFYING AND DISTRIBUTING DEVICE

Filed July 28, 1922

A technical cross-sectional drawing of a composite structure. The top layer is a thin, light-colored material with a wavy pattern. Below it is a thick, dark, cross-hatched layer. The bottom layer is a thick, light-colored material with a wavy pattern. On the left side, there are two vertical labels: '15' at the top and '19' below it. On the right side, there are three labels: '20' at the top, '30' in the middle, and '31' at the bottom. The drawing shows a central vertical channel with a wavy bottom, bounded by the three layers. The labels '15', '19', '20', '30', and '31' are positioned around the perimeter of this central channel.

ATTORNEY

UNITED STATES PATENT OFFICE.

NATHANIEL A. CLARK, OF DAVENPORT, IOWA.

SOUND AMPLIFYING AND DISTRIBUTING DEVICE.

Application filed July 28, 1922. Serial No. 578,175.

To all whom it may concern:

Be it known that I, NATHANIEL A. CLARK, a citizen of the United States, residing at Davenport, in the county of Scott and State 5 of Iowa, have invented new and useful Improvements in Sound Amplifying and Distributing Devices, of which the following is a specification.

The object of this invention is to eliminate the objectionable vibrations arising 10 from the reproduction of phonographic records, to amplify the sound, and to distribute it in the most effective manner possible, the natural tone being preserved.

15 A further object is to provide a particular form of amplifying chamber associated with a particular form of distributing device, whereby exceptionally good results are secured.

20 With the above and other objects in view, the invention consists in the novel construction and arrangement of elements described, illustrated, and claimed, it being understood that modifications may be made within the 25 scope of the claims without departing from the spirit of the invention.

In carrying out my invention, I provide a box including a motor board 10 and including side walls 11, 12, 13, 14, each side 30 wall being provided with an elongated opening 15 for the distribution of sound waves, in four directions.

The board 10 is provided with an aperture 17 for the tone arm 18, and the latter is in 35 communication with an amplifying chamber 19 having an upper wall or sound board 20, curved in the manner illustrated.

This element 20 is provided with openings 21, 22, which communicate with a

chamber 23, the board 20 including a portion 40 24 upwardly deflected and curved as shown. The upper wall of chamber 23 is designated 23'. Smaller chambers 25, 26 are located adjacent to the chamber 23 and on opposite sides of the throat portion 27. 45 The lower walls of the chambers 25, 26 are provided with openings designated 26'.

The sound board 20 includes a lower substantially horizontal portion which is approximately in alignment with the upper 50 edge of one of the openings in the side walls of the box, and the sound board 28 acting as a distributing device is in a line with the lower edges of all of the openings in the side walls, this arrangement being 55 particularly effective in attaining the objects sought to be realized.

A supplement board 30 is mounted below the board 28 and is provided with a central opening 31, forming an air chamber 32 60 serving to modify the effect of the vibrations on element 28.

What is claimed is:

In a device of the class described, a box 65 including a top, and side walls having openings near the bottom thereof, a sound board extending in the form of a curve from one side wall at a point above the opening therein, and having one edge spaced from the opposite wall, means forming a throat portion 70 in the space thus provided, and a sound board below the curved sound board and below the openings in the side walls, and constituting the lower wall of an amplifying 75 and distributing chamber having communication with the throat portion.

In testimony whereof I affix my signature.
NATHANIEL A. CLARK.
